UNITED STATES PATENT OFFICE.

JAMES MINERS HOLMAN AND JOHN LEONARD HOLMAN, OF CAMBORNE, ENGLAND.

ROCK-DRILL.

1,029,294.

Specification of Letters Patent. Patented June 11, 1912.

Application filed June 22, 1911. Serial No. 634,687.

To all whom it may concern:

Be it known that we, JAMES MINERS HOLMAN and JOHN LEONARD HOLMAN, both subjects of the King of Great Britain, residing 5 at Camborne, Cornwall, England, have invented new and useful Improvements in Rock-Drills, of which the following is a specification.

Our invention relates to rock-drills of the 10 type wherein the distributing valve is operated through the medium of a pivoted rocker which engages with the said valve, and which receives its motion from inclines or tappets upon the piston.

15 In drills of this class as hitherto constructed it has been usual to so construct the rocker that the ends thereof extend into the cylinder and are directly acted upon by tappets or by the piston during the reciprocation of the latter.

The object of our invention is to improve 20 upon this construction, and to this end the ends of the rocker, instead of projecting into the cylinder, are made somewhat shorter than heretofore and balls are interposed between these ends and the piston, the said 25 balls resting upon seats, the balls projecting so far into the cylinder that they will be pushed back by the piston or the tappets 30 during the reciprocation.

Our invention will be readily understood by reference to the accompanying drawing, which is a sectional view of a portion of a 35 rock-drill having our improvements applied to it.

a indicates the working cylinder, *b* the piston reciprocated therein, and which is formed with a recess as indicated at *c* in a well-known manner, *d* the air chamber, *e* 40 the distributing valve and *f* the tappet or rocker by means of which the said valve is operated and which receives its motion from tappets or inclines on the piston.

g, g are the balls which we arrange in accordance with our invention, in connection 45

with the said tappet, the said balls being carried in bushes or sockets *h* adjacent to the arms of the rocker, in such a manner that they project into the path of the piston, so that, as the latter reciprocates, the requisite rocking movement will be imparted to the rocker. 50

With this construction it will be understood that the wear which takes place between the points of contact is much less than 55 hitherto, owing to the fact that the balls *g, g* will rotate and present all parts of their surfaces at one time or another to the action of the tappets or inclines on the piston.

It will also be seen that the bushes or sockets *h* have their apertures reduced at their inner ends to hold the balls from projecting more than a slight distance into the cylinder and thereby hold them out of contact with the reduced or recessed portion of the piston. 60 The balls *g, g* therefore only come into contact with a portion of the inclined shoulders *b', b'* of the piston at each end of the piston stroke, thus greatly reducing the wear on the piston and balls. 65

Claims:

1. In a rock drill, the combination with a working cylinder, and a piston therein provided with a recessed portion, and inclined actuating shoulders, adjacent to said recessed portion, of a distributing valve for said cylinder, a pivotal rocker operatively connected with said valve, and provided with actuating arms, a ball located adjacent to each of said arms, and having a portion 75 extending into the path of said piston, and means for holding the ball out of contact with the recessed portion of said piston between the inclined shoulders thereof. 80

2. In a rock drill, the combination with a working cylinder and a piston therein provided with a recessed portion and an inclined actuating shoulder at each end of said recessed portion, of a distributing valve for the cylinder, a pivoted rocker operatively 85

connected therewith, and provided with actuating arms on opposite sides of the point of pivoting of said rocker, the cylinder being provided with an aperture in its wall 5 adjacent to each of said actuating arms, a bushing located in each of said apertures, and a ball located in each of said bushings, and having a part projecting into the path of the said inclined actuating shoulders of 10 the piston, said bushings having reduced apertures at their inner ends, to hold said balls out of contact with the piston except

at the instant of operative contact with said inclined actuating shoulders of the piston.

JAMES MINERS HOLMAN.

JOHN LEONARD HOLMAN.
